COMBINED LIPSTICK AND CONTAINER THEREFOR

Evelyn Bernard, Teaneck, N.J., assignor to Lehn & Fink
Products Corporation, New York, N.Y., a corporation of Delaware

Filed Apr. 14, 1964, Ser. No. 79,495

Term of patent 14 years

(Cl. D86—10)

FIGURE 1 is a perspective view of a combined lipstick and container therefor, showing my new design with the cover portion removed therefrom;

I claim:

The ornamental design for a combined lipstick and container therefor, as shown.
